Primary Examiner—Louis S. Zarfas*Assistant Examiner*—Eric Watterson*Attorney, Agent, or Firm*—Myron B. Kapustij; Malcolm J. Sutherland[57] **CLAIM**

The ornamental design for a two handle faucet spout cap, as shown and described.

DESCRIPTION

FIG. 1 is a top perspective view of a two handle faucet spout cap showing my new design;

FIG. 2 is an elevational view thereof; and,

FIG. 3 is a top plan view thereof.

The broken line showing of the faucet and handles in FIG. 1 is for purposes of illustration only and forms no part of the claimed design.
